UNITED STATES PATENT OFFICE.

ADOLPH ECKHARDT, OF SUTTON, NEBRASKA.

SPARK-PLUG.

1,159,911.

Specification of Letters Patent.

Patented Nov. 9, 1915.

Application filed October 8, 1914. Serial No. 865,728.

To all whom it may concern:

Be it known that I, ADOLPH ECKHARDT, citizen of the United States, residing at Sutton, in the county of Clay and State of Nebraska, have invented certain new and useful Improvements in Spark-Plugs, of which the following is a specification.

This invention relates to certain new and useful improvements in spark plugs for internal combustion engines and has as its primary object to provide a spark plug having a plurality of sparking points and wherein the spark gaps or the distance between the sparking points may be simultaneously adjusted.

The invention has as a further object to provide an improved device of this character including an integrally formed electrode which will be detachably connected 20 to the plug and which will provide a plurality of sparking points having sparking terminals detachably connected thereto to the end that either of said terminals may be selectively removed to be replaced by 25 a new terminal, or, on the other hand, that the entire electrode including its terminals may be removed. And a still further object of the invention is to provide an improved spark plug of the above described character 30 including an electrode having a plurality of sparking points and provided with a single terminal by which the said electrode may be connected with a suitable source of electrical energy.

With these and other objects in view my invention will be more fully described, illustrated in the accompanying drawings and then specifically pointed out in the claims which are attached to and form a part of 40 this application.

In the accompanying drawings: Figure 1 is a vertical sectional view of my improved spark plug showing the parts thereof in assembled relation, and Fig. 2 is a detail perspective view of the electrode carried by the insulating member of the plug and showing the said electrode detached.

Corresponding and like parts are referred to in the following description and 50 indicated in all the views of the drawings by the same reference characters.

My improved spark plug is especially designed for use upon internal combustion engines to have detachable connection with 55 the cylinders thereof to communicate with the ignition chambers of the engine in the

usual manner. More particularly, the plug includes a metallic shell 10 which is reduced intermediate its ends to provide an internal annular shoulder 11, the reduced extremity 60 of the shell being externally screw threaded as at 12 to engage within a suitable threaded bore formed in an engine cylinder. At its upper extremity, the shell 10 is provided with a squared head 13 disposed for engagement with a wrench or other tool.

Seated within the shell 10 is an insulating plug or member 14 which may be formed of porcelain or any other suitable material. Formed on the plug 14 intermediate its ends, is an annular shoulder 15 disposed to confront the shoulder 11 of the shell and interposed between the said shoulders is a gasket or packing ring 16 which may be formed of rubber or any suitable 75 fibrous material.

The shell 10 at its upper extremity is internally screw threaded to detachably engage an externally screw threaded collar 17, the said collar being disposed to surround 80 the plug 14 and being arranged to engage at its inner extremity against the shoulder 15. At its upper extremity, the collar 17 is provided with a laterally extending flange 18 arranged to seat against the upper 85 extremity of the shell 10 and provided with flat side faces disposed for engagement with a suitable wrench. It will be observed that the collar 17 is disposed to force the shoulder 15 of the plug down into engagement 90 with the gasket 16 to thus maintain the plug firmly in position within the shell and that the shell, the plug, and the collar may be readily detached from each other.

The inner extremity of the plug 14 is 95 preferably tapered toward its free end so that it may be easily fitted within the reduced extremity of the shell 10, and formed in the plug adjacent opposite sides thereof, are longitudinally extending bores 19 arranged substantially parallel with the vertical axis of the plug and opening at their extremities through the opposite end walls thereof.

Detachably mounted upon the plug 14 105 is an electrode which I have illustrated in Fig. 2 of the drawings and indicated as a whole at 20. More particularly, the electrode 20 includes a threaded terminal 21 which is bifurcated at its inner extremity 110 to provide members 22 extending laterally upon each side of the terminal 21, the mem-

bers 22 at their outer extremities being bent to provide oppositely disposed arms 23 arranged substantially parallel to each other. At their outer extremities, the arms 23 are 5 screw threaded to detachably engage the sparking terminals or points 24 while the terminal 21 is disposed to receive a suitable thumb nut 25.

As shown in Fig. 1 of the drawings, the 10 arms 23 of the electrode are disposed to extend through the bores 19 with the sparking terminals 24 seating against the adjacent lower face of the plug and with the members 22 of the electrode countersunk within 15 the upper extremity of the plug. By this arrangement, it will be seen that the electrode 20 may be readily detached from the plug 14 when desired by removing the sparking terminals 24 and this is a very desirable 20 feature of the construction which I provide since should the electrode 20 become damaged in use, it can be readily replaced. In this connection, it is also to be observed that should the sparking terminals 24 be 25 come burnt in use or damaged, the said terminals may be readily detached and new ones substituted therefor.

Removably fitted over the upper extremity of the plug 14 is a preferably metallic 30 cap 26, the said cap surrounding the terminal 21 of the electrode and providing a seat for a conductor carrying a suitable source of electrical energy and disposed to be connected with the terminal 21 by the nut 25.

Seated within the shell 10 at its outer extremity, are members 27 which are bent to extend radially toward the axis of the plug and provide sparking points 28 disposed to 35 coöperate with the sparking terminals 24 of the electrode 20. It will be observed that by turning the plug 14 within the shell 10, that the distance between the sparking terminals 24 and 28 may be adjusted to consequently regulate the length of the spark gap 40 between the said points and that in thus turning the plug 14, simultaneous adjustment will be had between each of the terminals 24 and the adjacent terminal 28 coöperating therewith.

As is well known, in the type of spark 50 plug employing a single spark gap, the sparking terminals often become sooted or burnt to render the plug inefficient and in the provision of my improved plug employing an integrally formed electrode having a plurality of sparking terminals, the electrical current passing through the electrode is distributed between the said terminals so that the likelihood of the burning thereof is 55 greatly lessened as compared with a construction wherein but a single spark gap is employed. I consequently provide a construction, in employing a plurality of spark gaps, one electrode of each of which is connected with a common conductor, wherein 60

the durability of the plug will be enhanced, while at the same time, should the sparking terminals of one spark gap become inoperative, the plug will still continue to give efficient service through the operation of the 70 other spark gap.

It will therefore be seen that I provide a very simple and efficient construction of spark plug wherein a plurality of spark gaps are employed, and wherein the length 75 of the said gaps may be simultaneously adjusted. It will further be seen that I provide a construction wherein a common electrode is employed for each of said gaps which may be readily detached to permit of 80 repair and wherein the sparking terminals connected with the said electrode may also be each disconnected therefrom either to effect the removal of the said electrode from the plug or to permit of repair or replacement of the said sparking terminals. 85

Having thus described my invention, what I claim and desire to secure by Letters Patent is:—

1. In a device of the character described, 90 the combination with a shell having sparking points and an insulating member, of an electrode carried by the insulating member, said electrode including a terminal disposed for connection with a suitable source of electrical energy and bifurcated at one extremity to provide members extending upon opposite sides of the terminal, said members being thence bent to provide spaced arms screw threaded adjacent their outer extremities, the electrode being disposed to seat upon the insulating member with the members of the electrode counter-sunk within the upper end of the insulating member and with the arms of the electrode extending through the said member, and sparking terminals screw threaded to engage the threaded extremities of said arms, said sparking terminals being disposed to coöperate with the sparking points of the shell. 100

2. A device of the character described including a shell having members arranged thereon providing sparking points, an insulating member carried by the shell, the said insulating member having longitudinally extending bores formed therein adjacent opposite sides, an electrode including a terminal disposed to receive a suitable conduit and having spaced arms extending from said terminal and disposed in said 110 bores, and sparking terminals detachably secured to the outer extremities of said arms and detachably connecting the electrode with the insulating member, said sparking terminals being disposed to coöperate with 115 the sparking points carried by the shell.

3. A device of the character described including a shell, an insulating member carried by the shell, members arranged upon the shell and providing sparking points, a 120

substantially U-shaped electrode having its arms extending through the insulating member, and sparking points carried at the free ends of said arms and detachably connecting the electrode with the said insulating member, said last mentioned sparking points being adapted to coöperate with said first mentioned sparking points.

4. A device of the character described including a shell, an insulating member carried by the shell, members arranged upon the shell and providing sparking points, an electrode removably fitted upon the insulating member and having spaced terminals,

and sparking points engaging said terminals 15 and seating against the said insulating member for detachably connecting the electrode with the insulating member, said last mentioned sparking points being adapted to coact with said first mentioned sparking 20 points.

In testimony whereof I affix my signature in presence of two witnesses.
